UNITED STATES PATENT OFFICE.

HENRY PLATT HALL, OF OLDHAM, ENGLAND.

CARRIAGE FOR SELF-ACTING MULES.

Application filed February 22, 1921. Serial No. 446,986.

To all whom it may concern:

Be it known that I, HENRY PLATT HALL, a subject of the King of the United Kingdom of Great Britain and Ireland, and 5 resident of "Toravon" Werneth, Oldham, in the county of Lancaster, England, have invented new and useful Improvements in Carriages for Self-Acting Mules, of which the following is a specification.

10 This invention consists in carriages for self acting mules constructed wholly or in great part of steel or other metal plate and constructions and devices to be applied in them which in comparison with the carriages heretofore made wholly or in great part of 15 steel or other metal plate or sheet and the constructions and devices applied in them, afford the advantages that in proportion to their weight, the carriages have greater 20 strength, rigidity and capacity to withstand the strains and shocks of use and are better altogether and the construction of carriages of the various lengths requisite is made more practicable.

25 For the attainment of these advantages the invention, relating to carriages constructed wholly or in great part of steel or other metal plate, consists in devices and constructions to be applied in such carriages 30 which are hereinafter to be described and particularized in the claims.

According to this invention a continuous 35 box girder of steel or other metal plate is provided as the main structure on which the other parts of a carriage of a self acting mule are mounted.

The box girder is constructed of any suitable 40 number of sections of suitable, and advantageously equal, length connected one to another after formation to build up a continuous box girder of the length requisite for a carriage to be formed.

Although plates of other metal may be 45 used steel plate will ordinarily be used in the formation of carriages according to this invention and so in the description following "steel plate" will generally be mentioned for simplicity.

In the accompanying drawings, Fig. 1 is 50 a vertical section through part of a carriage of a self acting mule showing one construction of box girder, the means for connecting the carriage bearers and one form of rest for the spindle rail or spindle box. Fig. 2

is a front elevation of some of the parts 55 shown in Fig. 1.

Fig. 3 is a transverse section through part 60 of a carriage showing another construction of box girder.

Fig. 4 is a front elevation illustrating 65 parts at and near the junction of two sections or portions of the length of the carriage shown in Fig. 1.

Fig. 5 is a transverse section through part 70 of a carriage comprising a box girder of 65 the construction shown in Figs. 1 and 2 and shows in side elevation one of the bearing brackets for the tin roller shaft and the means by which the bearing bracket shown is fixed in position.

Fig. 6 is a section illustrating a jogged 75 spindle rail rest riveted to the front wall of a section of a carriage and Figs. 7 and 8 are sections illustrating jogged spindle rail rests.

The same numerals of reference are employed 75 to indicate corresponding parts in all the figures.

In one construction of continuous box 80 girder mule carriage illustrated by Figs. 1, 2, 4 and 5 according to this invention the requisite number of sectional lengths I, of which only one is shown in Figs. 1, 2 and 5, and parts of two are shown in Fig. 4 may be made up by way of example: primarily 85 of a bottom plate 1 with upwardly directed flanges at the front and back to form the front 2 and back 3 of the section I and a top plate 4 provided with upwardly directed flanges 5, 6, along the edges to extend lengthwise of the section. The top plate is placed 90 and riveted in position between the front and back of the section and the bottom plate having the flange 2 extending above the flange 5 has secured to it by rivets 7 an upper plate 95 8 to extend vertically on the front wall and upwardly therefrom and beyond the top plate 4 and furnished at an appropriate height above the place of attachment of the plate 8 with a rearwardly extending inclined flange 9 serving in the completed carriage as a rest 100 for the spindle rail or spindle box 10 and forming a simple means of providing a rest at any height requisite and easily to be taken away and replaced by another plate if after 105 a carriage has been constructed it is necessary or desirable to provide a flange at a different height for spindles of different

length to be used or change of position of spindles.

Rivets 7 serving only for the attachment of the plates 8 are advantageous in that if it should be desirable to substitute for the plates 8 shown, other similar plates with flanges 9 at a different height, the rivets 7 securing them can be easily removed without interference with the fastening of any parts other than the plates 8 but, if it is convenient in any cases the plates 8 may be secured by the rivets used in securing together the front 2 and top 4.

The plates 8 are shown as presenting plane front surfaces but if desirable in any case, for the sake of greater stiffness in the plates 8 and consequent stiffening to the carriage front or for any other reason, the plates 8 may be jogged to present on each face parts in two approximately parallel planes so that the upper parts will be brought further towards the front or further towards the rear of the carriage than in the case shown in Figs. 1, 2, 4 and 5.

In Figs. 6, 7 and 8 illustrative examples of jogging are shown. Fig. 7 shows a spindle rail rest 100 jogged at 101 so that each face presents parts in two parallel planes and the upper part is further to the rear than the lower and Fig. 6 shows such a spindle rail rest 100 riveted to the front wall of a mule carriage section 102.

Fig. 8 shows a spindle rail rest 103 jogged at 104 so that each face presents parts in two parallel planes and the upper part further forward than the lower.

The fronts 2 of the sections I to be joined together and the plates 8 if attached to them may be made to meet throughout the adjoining parts, but if, as is preferable a plate or sheet 11 of metal to be described hereinafter is to be interposed between the meeting parts of the sections I the fronts 2 to be joined and the plates 8 if attached to them are made to meet in their upper parts and cut away in their lower parts so that space is provided for the plate 11.

In another construction of continuous box girder mule carriage according to this invention and illustrated in Fig. 3, the sectional lengths II of which only one is shown may be made up by way of example: primarily of top and bottom and front and back steel plates marked respectively 13, 14, 12, 15 riveted together, of which the top and bottom steel plates 13, 14 are provided respectively with upwardly and with downwardly directed flanges marked 16, 17, respectively along the edges to extend lengthwise of the sections II. The back plate 15 is a plain plate to which other parts may be attached and the front 12 is made to present an extension 81 extending upwardly beyond the rivets 71 securing the top plate 13 and furnished with a rearwardly directed in-

clined flange 91 serving in the completed carriage as a rest for the spindle rail or spindle box.

In each of the constructions hereinbefore described the top plates 4 or 13 of a section 70 may be of the same length as the bottom plate 1 or 14 but, if either be the shorter, it may be secured to another or others in any appropriate manner as for example by the parts to be joined together being furnished 75 with flanges or angle bars upwardly directed in the case of a top plate or downwardly in the case of a bottom plate, secured one to another immediately or with the interposition 80 of a transverse plate or a flanged plate riveted to the bottom or top or front and back or both to the bottom or top and front and back to stiffen the structure.

In each of the constructions hereinbefore described the rivets for securing together 85 the longitudinal edges of the top and bottom plates or top and bottom and front and back plates are outside the internal cavities of the sections and any rivets to enter those cavities at parts inaccessible from the ends 90 may be applied before the plates are riveted together.

A section of a continuous box girder to be placed next the square at either side of the headstock of a self acting mule may be made 95 with a top, bottom and side of steel plate thicker than, for example, twice as thick as that used for other sections.

According to this invention in order that one section of a continuous box girder self 100 acting mule carriage may be coupled to another adjoining it, or a section may be attached to a square of a self acting mule or that a section to form the end of a carriage remote from the square may be adapted to 105 have an end plate secured to it, each section is provided externally at each end with right angled flanged metallic attaching parts presenting only longitudinal bearing faces and having the two outer bearing faces at 110 right angles for one to bear against the section and the other to bear against a part for connection with said section and formed with holes for bolts. The right angled flanged metallic attaching parts may be in 115 the form of angle plates or flanged brackets and are riveted to it at the top and bottom or the front and rear or to it at the top and bottom and flanged brackets riveted to it at the front and rear or a flanged plate riveted 120 at the top or bottom and at the front or rear or front and rear to present holes formed in their flanges opposite to holes in the flanges of similar right angled metallic attaching parts on the section or to holes in the square 125 to which it is to be joined or end plate to be joined to it. Preferably the right angled metallic attaching parts on the bottom of a section are riveted thereto before the top plate is riveted in position. Bolts passed 130

through the holes in the flanges of angle plates or flanged brackets or the right angled metallic attaching parts riveted to a section are used to secure one section to another or to the square of a mule carriage or an end plate to the section as the case may be. A steel plate to extend from front to rear between the meeting faces of sections to be joined together may be provided to add rigidity to the continuous box girder and to be secured in position by the bolts securing the sections together and the plate so used may serve also to carry any other part or parts.

Fig. 3 showing one end of the section II shows flanged plates 18, 19, riveted respectively to the top 13 and bottom 14 of the section and flanged brackets 20, 21, riveted respectively to the front 12 and back 15 and a metal plate or sheet 11 corresponding in outline with the outer edges of the flanged plates 18, 19 and flanged brackets 20, 21 and the end of the section II. The flanged plates 18, 19 and the flanged brackets 20, 21 are so formed and riveted in such positions on the section II that they present faces in one plane and in the same plane as the ends of the plates or sheets forming the top 13, bottom 14, front 12 and back 15 of the section II. The flanged plates 18, 19 and flanged brackets 20, 21 being provided with bolt holes and corresponding bolt holes being formed in the plate 11 bolts 22 are passed through these holes and holes in flanged plates and flanged brackets on the section and corresponding to the plates 18, 19 and brackets 20, 21 and are provided with nuts which being tightened secure the sections firmly together, the plate 11 stiffening the section.

Figs. 4 and 5 illustrate flanged plates 119 riveted on the bottoms 1 of the sections I and flanged brackets 120, 121 riveted respectively on the front and rear 2, 3 respectively of the sections I and a plate 111 secured between the flanged plates 119 and flanged brackets 120, 121 of the two sections I by means of bolts 22 passed through holes in the flanged plates 119 and flanged brackets 120, 121 and the interposed plate 111, the plate 111 being shaped to correspond with the outline presented by the outer edges of the flanged plate 119, flanged brackets 120, 121 and the meeting parts of the sections joined together, and as in the construction shown in Fig. 3 the plate 111 stiffens the section I.

The flanged plates and brackets corresponding to those described with reference to Figs. 3, 4 and 5 serve also for the attachment of the continuous box girder carriage to the square of a self acting mule which will be provided with holes in appropriate parts of the framework for the attaching bolts but advantageously the angle

plates or brackets used for connection to the square may extend for a greater length on the front or rear as the case may be of the section than the corresponding parts at the other end of the section.

The section to be at the end of a self acting mule carriage remote from the square may serve for the attachment of the end plate to be there provided which obviously will be provided with holes in appropriate places for the bolts requisite.

According to this invention in order that carriage bearers may be secured in any positions requisite upon continuous box girders used in mule carriages angle bars 23 are provided on and in the preferred constructions made as shown in Figs. 2 and 4 to extend along sections of the girders and channel bars 24 with parts of the flanges made to extend as ears 25 transversely from the ends, are applied with the flanges upwards transversely on the bottoms 1 on the sections I of the box girders and riveted or advantageously bolted to the angle bars 23. The ears 25 are shown as formed with holes through which the rivets securing the channel bars 24 to angle bars 23 are passed. In a preferred construction the angle bars are provided as shown in Figs. 2 and 4 with holes at equal intervals along their length so that the channel bars 24 may be attached to any of a number of places. The channel bars 24 are provided with holes in which rising screws 26 of any convenient form as screws, bolts or studs attached to or serving for attachment of the carriage bearers 27 are secured and preferably to facilitate the application of the rising screws if the holes for them should be accessible from one side only in use as in the case shown in the drawings these holes are formed large enough to allow passage of nuts or bolt heads or the like and the rising screws into communicating slots in which the shanks or like parts of the screws may be secured by nuts.

Of the two channel bars 24 shown one is furnished near one end and the other near each end with a hole and communicating slot to serve respectively for the passage of the head and the passage of the shank of a rising screw 26, the three rising screws being connected to the carriage bearer 27 in an ordinary manner. When the channel bars 24 have been applied on the bottom 1 or 14 of the section I or II of the carriage and secured to the flanges or angle bars 23 the heads of the three rising screws are introduced through the holes into the spaces within the channel bars 24 and the shanks 125 are slipped into the communicating slots and secured therein by means of the nuts 28 and the rising screws are adjusted and secured in position in the carriage bearers 27 in the ordinary manner for the sections I, 130

II of the carriage to be supported in the manner requisite by the wheels of the carriage bearers 27. Other channel bars 24 like the two shown are applied wherever convenient on the sections I or II and elsewhere on the carriage for the connection of carriage bearers.

According to this invention in order that bearing brackets for the tin roller shafts 10 may be mounted and made adjustable upon the continuous box girder carriage of a self acting mule, channel bars 29 with parts of the flanges made to furnish at the ends ears 30 at right angles to the bars are applied 15 with flanges downwards transversely on the top plates 4, 13 of the sections I, or II of the box girder are riveted or bolted at their ends to the plates of each section. Each channel bar 29 is made to bear one of the 20 bearing brackets 31 for the tin roller 32 to extend along the girder, the bolts or studs 33 for securing the bearing bracket 31 to the channel bar 29 being introduced into the holes provided for them through a gap 25 formed in one of the flanges of the channel bar 29 but if convenient in any case the channel bar 29 may be provided with holes and communicating slots to allow passage respectively for the heads and the shanks 30 of the bolts 33 which may then be passed from above through the holes and into the slots in it. Brackets 34 secured to the channel bars by means of rivets, by means of bolts passed through holes with communicating slots like those aforesaid or in any other way or other means may be provided to afford screw threaded holes or other appropriate bearing for screws 35 with lock nuts for adjusting and fixing the adjustment of the bearing brackets lengthwise of the channel bars 29.

Further according to this invention in order to provide for the attachment of the tie rods for adjusting and fixing the position of the spindle rails or spindle boxes 10 angle bars 36 made to extend from front to back of sections formed in any of the ways hereinbefore described are riveted in position preferably to the top plate, by means 45 of one flange, and brackets 37 generally similar in their upper parts to those used for providing attachment for the upper tie rods on wood mule carriages which are adapted at their lower parts to be fitted and secured by bolts to the angle bars provided 50 in their upper parts with ears with suitably formed curved faces and holes allowing sufficiently free passage for the upper tie rods 38, so that the nuts on the tie rods 38 55 may be made to fix them in any position into which they may be swivelled in adjustment of the spindle rails or spindle boxes 10 on the bracket 37 may be furnished with eye bolts or studs providing attachment in 60 which the upper tie rods 38 are mounted to

swivel and secured by nuts in the arms of the brackets. Eye bolts or studs 39 are mounted to swivel and secured by nuts in the angle bars 36 to provide attachment for the lower tie rods 40. In modifications of 70 this construction other means for attaching the tie rods to the brackets and angle bars may be employed.

Longitudinal rails 41 secured to the several mountings for the tie rods 38 of the 75 spindle rails or spindle boxes 10, the square of the headstock and the end plates of the carriage as the case may be, are provided for the support or attachment of the rear edges of top covers 42 and the upper edges 80 of rear covers 43.

The longitudinal rails 41 are formed of sections bolted or riveted together into continuous rails.

The top covers 42 are formed of steel 85 sheet in convenient lengths and of widths sufficient to enable them to overlap to the extent necessary the upper spindle rail or spindle box 10 at the front and the longitudinal supporting rails 41 at the rear. 90

In the case illustrated the top covers 42, of which only one is shown, are provided at the rear with folded edges 44 to embrace the edge of the rail 41 and at the front with a beaded edge to rest on the spindle rails 95 or spindle boxes 10.

In the case illustrated the rear covers 43, of which only one is shown are made of steel sheets and made to slide in grooves in the brackets 37 and bent rearwardly at the 100 lower parts to rest upon the section I of the continuous box girder and provided on their inner faces with ears 45 to engage the upper rear flanges of the sections to prevent the covers 43 from being displaced rearwardly 105 and on their upper parts are provided with forwardly bent parts 46 to bear upon the rails 41.

Front covers 47 may be made of sheet metal in convenient lengths in any way 110 convenient and made to overlap or to enter or to be engaged in any convenient way with the front walls of the sections.

The spindle rails or spindle boxes 10 are advantageously formed of longitudinal 115 wood rails connected by metal or other brackets.

This invention may be applied to a self acting mule with a carriage at both sides or only at one side of the headstock, the construction applied in any case in which there is a carriage at only one side of the headstock being equivalent to that applied at the part of a carriage at one side of the headstock of a self acting mule having a carriage 125 at both sides of the headstock.

The faller relieving motions and middle drawing out tightening arrangements which are of ordinary construction and therefore not shown may be supported by any con- 130

venient means for example, brackets much like those ordinarily used on wooden carriages of self acting mules for carrying the faller relieving motions and middle drawing out tightening arrangements and riveted to the upturned parts of or at the front and rear of the sections of a mule carriage to angle bars provided at the bottom. The faller shaft and counterfaller shaft which are of ordinary construction (omitted from the drawing for simplicity) may be carried in uprights riveted or otherwise secured in convenient positions to the sections of the carriage or to parts applied thereon.

15 What I do claim as my invention and desire to secure by Letters Patent is:—

1. A self acting mule carriage formed as to its main structure of a continuous box girder of sheet metal.

20 2. A self acting mule carriage formed as to its main structure of a continuous box girder of sheet metal and characterized by being formed in sections, each comprising a bottom plate with upwardly directed flanges at the front and back of the section, and a top plate with upwardly directed flanges along the edges to extend lengthwise of the section and riveted to the bottom plate along these edges.

25 3. A self acting mule carriage formed as to its main structure as a continuous box girder, characterized by a channel bar which having parts of the flanges made to extend transversely from its ends is applied flanges downwards on the top plate of a section and is secured at its ends to plates of the carriage and is adapted to have a tin roller bearing bracket mounted upon it and is furnished with a block, and an adjusting

40 device in connection with such block for adjusting such bracket lengthwise of the channel bar.

45 4. A self acting mule carriage formed as to its main structure as a continuous box girder, characterized by a channel bar which is formed with a hole or holes and a communicating slot or slots for the reception of

bolts and is adapted to have a tin roller bearing bracket mounted on it and is furnished with a block and an adjusting device in connection with such block for adjusting such bracket lengthwise of the channel bar.

5. A self acting mule carriage formed as to its main structure as a continuous box girder, characterized by an angle bar which is riveted to the top plate of a section, a bracket bolted to the angle bar, and upper tie rod for a spindle rail or spindle box attached to such bracket and a lower tie rod for a spindle rail or box attached to the angle bar.

6. A self acting mule carriage formed as to its main structure as a continuous box girder, supports mounted on such carriage at the rear to support a rail, a longitudinal rail made of sections of metal plate secured together into a continuous rail secured to such supports and covers applied to such rail by their edges.

7. A self acting mule carriage formed as to its main structure as a continuous box girder, supports mounted on such carriage at the rear to support a rail, a longitudinal rail made of sections of metal plate secured together into a continuous rail secured to such supports and top covers of sheet metal having the rear edges folded to embrace the longitudinal rail.

8. In a self acting mule carriage formed as to its main structure as a continuous box girder, sections of such carriage and rear covers applied at the rear of the carriage and engaging means on such rear covers for engaging the rear walls of sections of the carriage.

In testimony, that I claim the foregoing as my invention, I have signed my name in presence of two witnesses, this eighth day of February 1921.

HENRY PLATT HALL.
